(57) **CLAIM**

The ornamental design for a card cutting mat, as shown and
described.

DESCRIPTION

FIG. 1 is a top plan view of a card cutting mat;
FIG. 2 is a front elevation view of the card cutting mat of
FIG. 1, the rear elevation view thereof being a minor image
of this front elevation view;
FIG. 3 is a left side elevation view of the card cutting mat
of FIG. 1, the right elevation view thereof being a mirror
image of this left elevation view; and,
FIG. 4 is a bottom plan view of the card cutting mat of FIG.
1.

(Continued)

The broken lines in the figures show portions of the card cutting mat that form no part of the claimed design. The "cricut" lettering and/or icon forming part of the disclosure is a registered trademark of Cricut, Inc.
